UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP-MOTION.

1,352,529.

Specification of Letters Patent. Patented Sept. 14, 1920.

Application filed April 15, 1920. Serial No. 374,025.

To all whom it may concern:

Be it known that I, JOHN REGAN, a citizen of the United States, residing at New Bedford, in the county of Bristol and State 5 of Massachusetts, have invented a new and useful Warp Stop-Motion, of which the following is a specification.

This invention relates to a warp stop motion of the type shown in my prior Patent 10 No. 1,365,121, of May 7, 1918.

In the practical operation of the patented stop motion, occasional instances have occurred in which a drop wire has been caught and held up by an adjacent drop wire.

15 This may occur when warp threads are passed through adjacent drop wires from opposite sides, so that the wires tend to stand at opposed angles instead of in parallel relation. Under such conditions the 20 slot in one wire may be caught over an upper corner of an adjacent wire and it will then be impossible for the caught wire to drop even if its warp thread is broken.

It is the general object of my present invention to provide means effective to prevent such displacement of the drop wire, to the end that every drop wire may be maintained at all times in operative position. My 25 improved construction also possesses certain other advantages which will be hereinafter 30 fully set forth.

A preferred form of my invention is shown in the drawings in which

Figure 1 is an end elevation of my improved stop motion;

Fig. 2 is a partial front elevation of the parts shown in Fig. 1;

40 Figs. 3 and 4 are diagrammatic end elevations showing the operation of the parts under different conditions;

Fig. 5 shows the position of the drop wire and indicator bar under normal conditions, and

Fig. 6 shows the position of the same parts 45 after the breaking of a warp thread.

The mechanism shown in the drawings is in general, substantially similar to that shown in my prior patent, and is mounted on a frame 10 adjustably secured to a rod

50 11 fixed to the loom side (not shown). The frame 10 is connected by bars 12 to a similar frame at the opposite side of the loom, the bars being separated laterally to permit drop wires 13 to hang freely between them.

In Fig. 1, I have indicated a stop motion 55 having two banks of drop wires and requiring three connecting bars 12. The drop wires 13 may be varied somewhat in design to suit different conditions but as shown in the drawings are slotted at the lower end 60 and are provided with openings 14 each having a wide lower portion 14^a and a narrow upper portion 14^b. An indicating bar 15 extends through the openings 14 in each bank of drop wires, being disposed in the 65 wide lower portion 14^a of the openings when the wires are in normal raised position. The bars 15 are preferably of non-circular cross section and each end of each bar is preferably supported in a bearing block 16, 70 mounted for angular movement in the frame 10.

At the operative end of the stop motion, each block 16 is provided with a downwardly extending arm 17 having a stud or 75 projection 18 at its lower end. A lock plate 20 is pivoted at 21 to the frame 10, and is held in operative position by a flange 22 resting upon a portion of said frame. When in operative position the plate 20 prevents 80 longitudinal removal of the indicator bars 15.

The stud 18 extends through slots 24 in the slotted lower end of a lever 25, pivoted on a stud 26 carried by an arm 27. The arm 27 is mounted to swing on a pivot 28 fixed to the frame 10.

The lever 25 extends upwardly beyond the stud 26 and at its upper end is provided with a stud 30 upon which is pivoted one 90 end of a link 31 through which the knock-off mechanism is controlled.

The arm 27 is regularly oscillated through an actuating link 32 by which the arm is connected to actuating mechanism 95 not shown. The arm 27 also supports a spring plunger 34 engaging a flat face on the lever 25, and by which the lever is retained yieldingly in the position shown in Fig. 1. For a complete description of suitable actuating mechanism for the link 32 reference is made to the patent to Wyman No. 665,713, issued January 8, 1901.

Under normal conditions the slotted lever 25 moves in unison with the arms 27 about 105 the pivot 28 as a center engaging the studs 18 and swinging the arms 17 to the right and left to the dotted line positions shown in

Fig. 3. The indicator bars 15 are thereby oscillated about the axes of the circular bearing blocks 16, and this free oscillation of the indicating bars will continue so long as the drop wires are all in the raised position shown in Fig. 5.

The principal novel feature of this application consists in providing a stationary bar 33 for each bank of drop wires, having 10 supporting bearings in the end frames 10 and extending through the wide lower portion 14^a of the drop wires, below the indicator bars 15.

The stationary bars 33 are preferably of 15 a width substantially equal to the width of the portions 14^a of the openings in the drop wires. This bar 33 acts to prevent sidewise movement of the drop wires, so that it is impossible for the portion 14^b of the opening 14 in any wire to be caught over an upper corner of its adjacent drop wire.

The operation of the stop motion on a warp break is as follows:—The corresponding drop wire falls to the position shown in 25 Fig. 6, engaging the indicator bar 15 between the sides of the narrow portion 14^b of the opening 14. When thus engaged further oscillation of the bar 15 becomes impossible and accordingly the arms 17 and studs 30 18 are held in the fixed position shown in Fig. 4. The studs 18 then act as fixed pivots for the slotted lever 25, which swings about the studs 18 and moves the link 31 to the right or left, as indicated in dotted lines in 35 Fig. 4. Such movement of the link 31 causes the knock-off mechanism to operate and stop the loom.

When a drop wire falls and prevents movement of the indicator bar 15, the stationary bar 33 furnishes a support for the drop wire somewhat closer to the indicator bar than the frame-bars 12, and thus en-

ables the drop wire to hold the indicator bar in a more positive manner. The bars 33 also act at times to prevent the warp threads 45 from being raised against the indicator bars as the shed is opened, and thus prevent interference with the oscillatory movement of the bars.

Intermediate supports, not shown, may be 50 provided for the stationary bars 33 when necessary, particularly when the lease bars are so arranged that the lift of the warp is taken by the bars 33.

I have shown the bars 33 as having substantially 55 the same cross-section as the bars 15, but the particular section is not important provided it is substantially equal in width to the portions 14^a of the openings 14.

Having thus described my invention, it 60 will be evident that changes and modifications may be made therein by those skilled in the art, within the spirit and scope thereof as set forth in the claim, and I do not wish to be otherwise limited to the details herein 65 disclosed, but what I claim is:—

In a warp stop motion, a plurality of drop wires, each with an opening therein having a relatively wide lower portion, and a relatively narrow upper portion, a normally 70 movable indicator bar extending through said openings and effective to engage both sides of said narrow portion of the opening in a fallen drop wire, yielding means to oscillate said indicator bar, and a stationary 75 bar also extending through said opening below said indicator bar and having a width substantially corresponding to the width of the wide lower portion of the opening in said drop wire.

In testimony whereof I have hereunto affixed my signature.

JOHN REGAN.
